UNITED STATES PATENT OFFICE

STEPHEN M. NEDESKY, OF DULUTH, MINNESOTA

DESIGN FOR A DOORCHECK BRACKET

Application filed April 26, 1929. Serial No. 31,018. Term of patent 7 years.

To all whom it may concern:

Be it known that I, STEPHEN M. NEDESKY, a citizen of the United States, residing at Duluth, in the county of St. Louis and State of Minnesota, have invented a new, original, and ornamental Design for Doorcheck Brackets, of which the following is a specification, reference being had to the accompanying drawing, forming part thereof.

Figure 1 is a front elevation of a doorcheck bracket, showing my new design, and Figure 2 is a perspective view of the same.

I claim:

The ornamental design for a doorcheck bracket, as shown.

STEPHEN M. NEDESKY.
